UNITED STATES PATENT OFFICE.

DALLAS F. GREEN, OF FORT WAYNE, INDIANA.

EYEGLASS-MOUNTING.

1,334,490.

Specification of Letters Patent. Patented Mar. 23, 1920.

Application filed May 9, 1918. Serial No. 233,480.

To all whom it may concern:

Be it known that I, DALLAS F. GREEN, a citizen of the United States, residing at Fort Wayne, in the county of Allen and State of Indiana, have invented new and useful Improvements in Eyeglass-Mountings, of which the following is a specification.

The invention relates to eye glass mountings and particularly to improvements in the type of such mountings known to the trade as finger-piece and Oxford mountings. The object of the invention is to produce a stable and durable mounting in which the 10 mechanical parts are so placed as to be concealed when on the wearer's face and also entirely out of the line or field of vision of the wearer's eyes. Another object is to shorten up the bridge arch and at the same 15 time keep the bearings entirely free of contact with the nose of the wearer. Another object is to obtain a movement of the nose guards in an arc parallel to the plane of the lenses and another object is to provide a 20 novel form of bearing for the movable parts which shall add stability and wearing qualities to the mounting and prevent unnecessary side action or wobbling in those parts. 25

In the accompanying drawings I illustrate an embodiment of the invention in which Figure 1 is a rear elevational view of a pair of eye-glasses provided with my improvement; Fig. 2, a plan view of the same; Fig. 3 an enlarged side elevational view of 30 the mounting, the bridge being omitted; Fig. 4 an end view of the same; Fig. 5 a side elevational view of the lens strap; Fig. 6 an end view of the same and Fig. 7 a rear elevational view of a modified form of the invention.

In the Oxford type of lens mountings they are secured to the lenses at a point on the peripheral edge thereof above the middle point of the inner edge of the lens so 45 that the bridge in said type has been heretofore of a considerable length relatively to the bridges of other types of mountings.

Referring to the drawings, the mounting 50 consists of the bridge 10, secured at its opposite ends to straps 11. The straps and the parts secured thereto and operative thereupon are identical in construction, hence I shall describe but one of them. The strap is preferably stamped out of a single piece 55 of material and consists of two oppositely extending prongs 12 adapted to engage the

periphery of the lens 13 and two depending ears 14 which are engaged to opposite faces of the lens by screw 15 which is passed through apertures in the ears and the lens. 60 A bearing 16 is secured to the rear face of the rear ear 14 and projects rearwardly therefrom. The bearing is centrally apertured to receive the forward end of screw or post 17. A cylinder 18 is engaged on the periphery of the bearing and is revoluble thereon. The rear end of the cylinder is closed by wall 19 and the wall is centrally apertured to receive screw 17 and upon which screw the cylinder is also revoluble. 70 The head of the screw bears against the rear face of the wall 19 and retains the cylinder on both bearings. A coiled spring 20 is within the cylinder, one end thereof being engaged in an aperture 21 formed in bearing 16 and the other end is engaged in an aperture formed in wall 19. Guard arm 22 is secured to the cylinder and its forward end is projected forwardly and laterally to form a finger piece 23 which is above the 80 line of vision of the wearer's eye. The portion of the guard arm below the cylinder is relatively long and extends laterally and downwardly from the cylinder so that guard 24 secured to the lower end of the arm shall, 85 in its normal position, lie adjacent the inner edge of the lens and laterally of the vertical plane of the longitudinal axis of the pivotal point of the guard arm. The pivot of the guard formed by the bearing and the 90 screw 17 projects rearwardly from the lens strap and at right angles to the plane of the lens and it and cylinder 18 are therefore behind the lens strap and are invisible from the front side of the eye-glasses. Since the 95 guards are normally beyond the inner edges of the lenses the bearings and cylinders of the guards do not touch any part of the face of the wearer. By moving the finger pieces toward each other the guards are separated, 100 springs 20 opposing the movement. Upon releasing the finger pieces the springs restore or tend to restore the guards to normal position. Since the pivots, upon which the guards are mounted, project at right angles 105 to the plane of the lenses, the movement of each guard is in the arc of a circle and in a plane parallel to the plane of the lens and the gripping action of the guard is in an upward direction as it meets the side of the 110 nose of the wearer. The spring causes the guard to grip the side of the nose firmly and

since the guard is beyond its pivotal point relatively to the edge of the lens the weight of the lens tends to increase the gripping power of the guard since the lens strap is secured to the upper periphery of the lens rather than at approximately the middle of its inner edge as in other forms of mountings; that is, types other than the Oxford. It is apparent that the heavier the lens the greater will be its effect on the guard.

By constructing and arranging the pivotal points of the guards as above described I am enabled to use a much shorter bridge than heretofore in mountings of the Oxford type.

I may use my mounting on rims as well as on rimless glasses.

In Fig. 7 I illustrate the application of the invention in modified form in which I secure the ends of the bridge to the cylinders 25 which are identical in construction to cylinders 18 and are mounted on the lens straps 26 in the manner above described. The guards 27 are then secured to the lens straps, the arms 28 thereof depending from the straps and having their lower ends bent rearwardly and connected to the guards so that the guards shall be in the same position relatively to the cylinders 25 as guards 24 are to cylinders 18. Finger pieces 29 may be secured to the lens straps or they may be omitted. In this adaptation the lenses will be rocked upwardly on the pivots, the springs within the cylinders 25 opposing the movement as before. The guards 27, being secured to the lens straps, therefore move in arcs identical with the arcs in which guards 24 move and the same lateral and upward movement of the guards for gripping the sides of the nose of the wearer is obtained upon releasing the lenses as is obtained in the previously described adaptation of the invention. In both illustrations the grip of the guards is much firmer than in mountings where the movement of the guards is such that they merely impinge upon the sides of the nose of the wearer.

What I claim is:

1. In a lens mounting, a strap adapted to

be secured to the peripheral edge of a lens, 50 a pivotal bearing projecting rearwardly from the rear side of the strap, a cylinder revolvably mounted on the pivotal bearing and having contact therewith at its opposite ends, a coiled spring within the cylinder 55 and connected at one end to the cylinder and at its other end to the pivotal bearing, a bridge and a guard, one of the latter two members being connected to the cylinder and the other to the strap whereby, upon 60 relative movement between the cylinder and strap, the guard is moved in the arc of a circle.

2. In a lens mounting, a strap adapted to be secured to the peripheral edge of a lens, 65 a bearing formed on the rear side of the strap, a post projecting rearwardly from the bearing and at right angles to the vertical plane of the lens, a cylinder revolvably mounted at its opposite ends on the bearing and post and a guard connected to the cylinder and depending therefrom and in its normal position being in a vertical plane beyond the vertical plane of the longitudinal axis of the cylinder, and means within 70 the cylinder tending to retain the guard in said normal position.

3. In a lens mounting, a strap adapted to be secured to the peripheral edge of a lens, a bearing formed on the rear side of the 80 strap, a post connected to the bearing and projecting rearwardly therefrom and at right angles to the vertical plane of the lens, a cylinder having its rear end closed and apertured to revolvably engage the post and 85 having its forward end revolvably engaged on the bearing, a spring within the cylinder connected at one end to the bearing and at its other end to the cylinder, a bridge connected at one end to the strap, and a guard 90 connected to the cylinder which, in its normal position is below and beyond the cylinder.

In witness whereof I have hereunto subscribed my name this 29th day of April, 95 1918.

DALLAS F. GREEN.
